UNITED STATES PATENT OFFICE.

JAMES INNES, OF POWELL RIVER, BRITISH COLUMBIA, CANADA.

DRUMHEAD-TIGHTENING MEANS.

1,412,307.

Specification of Letters Patent. Patented Apr. 11, 1922.

Application filed March 30, 1921. Serial No. 456,805.

To all whom it may concern:

Be it known that I, JAMES INNES, citizen of the Dominion of Canada, residing at Powell River, in the Province of British Columbia, Canada, have invented certain new and useful Improvements in Drumhead-Tightening Means, of which the following is a specification.

This invention relates to a tension regulator for single tension drums. In such drums tension is simultaneously applied to the tightening hoops of both heads, either by cords or by several tension rods having a winged head, which rod passes through a member engaging the tightening hoop of one head and threaded into another member engaging the tightening hoop of the other head.

The snare head of a drum is usually of thinner material than the batter head, as it is required to vibrate freely under the impulses of the air transmitted from blows delivered on the batter head. Being thinner the snare head does not require to be tightened to the same extent as the batter head. When tensioned equally as under existing practice, the snare head being thinner is over-tensioned before the batter head is sufficiently tight.

This objection is overcome in the invention, which is the subject of this application by providing the hoop of the snare head with a tension regulator, which is supplementary to the single tension device with which the drum is provided, and is designed to relieve the snare head of any pressure beyond what it is desired that head should receive, and without interfering with the application of tightening pressure to the batter head.

The invention is fully described in the following specification, reference being made to the drawings by which it is accompanied, in which:

Fig. 1 is a side elevation of a single tension drum having my regulator applied to the lower or snare head.

Fig. 2 is an enlarged detail of the regulator in front view, and

Fig. 3, a side elevation of the same together with the adjacent parts of the drum.

Figure 4 is a perspective view of a modi-

fied arrangement of the regulator, herein-after referred to.

In these drawings 2 represents the cylinder of the drum, 3 being the tightening hoop and 4 the flesh ring of the batter head; 5 is the tightening hoop of the snare head and 6 the flesh ring of that head. These hoops 3 and 5 are drawn together to simultaneously tighten both heads by what is known as a single tension device shown at 7.

The tension regulator, which is the particular subject of this application, is designed to relieve the snare head 5 of any pressure beyond that which it should have, without interfering with the imposition of further tightening pressure on the hoop 3 of the batter head.

The device comprises a member 8 having provision for attachment to the cylinder 2 of the drum between each pair of the tightening devices 7 and adjacent the snare head hoop 5. This member 8 is threaded to receive a screw 9 having a milled head 10 of relatively small diameter to clear the cylinder of the drum, and having a swivel bearing piece 11 adapted to fit against the flesh ring 6 of the snare head.

These regulators as described are, when the snare head is tightened to the desired extent by the screws 7, adjusted to support the snare head hoop 5 against further tightening movement, as further movement of that hoop is stopped by the ends of the tightening screws 9 applied to the flesh ring 6.

While the snare head hoop 5 is stopped against further tightening movement, the tightening movement may be continued to any desired extent on the batter head hoop 3.

Obviously, if the snare head requires to be further tightened the regulating screws 9 may be uniformly slackened back and the tension screws 7 tightened to draw the snare head hoop up against the stop of the regulating screws 9.

The device is applicable to any drum having any single tightening device. It provides a simple and readily attached means enabling the heads to be independently tightened to any desired playing tension with the consequent advantages in improvement of tone, etc.

Instead of providing the regulating screw

9 with a swiveled bearing head 11, as is best shown in Figure 2, the lower end of the said screw 9 may bear directly against the top of the flesh ring 6 as is shown in Figure 4.

Having now particularly described my invention, I hereby declare that what I claim as new and desire to be protected in by Letters Patent, is:

- 10 1. In a drum having provision for simultaneously tensioning the two heads, means applicable to the tensioning hoop of one of the heads preventing the tensioning movement beyond a desired limit.
- 15 2. In a drum having provision for simultaneously tensioning the two heads, means applicable to the tensioning hoop of one of the heads preventing the tensioning movement beyond a desired limit, said means

comprising an adjustable means secured to 20 the cylinder of the drum adjacent one end preventing movement of the hoop at that end beyond a desired limit.

3. In a drum having provision for simultaneously tensioning the two heads, means 25 applicable to the tensioning hoop of one of the heads preventing the tensioning movement beyond a desired limit, said means comprising a member secured to the cylinder of the drum adjacent the tensioning hoop of 30 one end and intermediate the application of the tensioning means to that hoop, a screw threaded into said member the point of which screw bears against the flesh ring of 35 the head it is desired to relieve of further tension.

In testimony whereof I affix my signature.
JAMES INNES.
